KARL ETZRODT, OF BERLIN-SIEMENSSTADT, GERMANY, ASSIGNOR TO SIEMENS & HALSKE AKTIENGESELLSCHAFT, OF SIEMENSSTADT, NEAR BERLIN, GERMANY, A CORPORATION OF GERMANY

DEVICE FOR TAPPING SUPPLY LINES

Application filed May 23, 1930, Serial No. 455,003, and in Germany April 13, 1929.

This invention relates broadly to a constant current arrangement and more specifically to the use of hydrogen-iron resistances for maintaining the current in line tapping devices constant. According to one proposal the hydrogen-iron resistance may be connected in the lead to the primary winding so that the variations of the line have no influence on the device or the circuits fed by the latter, in particular the heating circuits of hot cathode tubes. However, as is well known, different alternating current supply lines carry different voltages, as for instance 110 or 220 volt. In order not to necessitate the keeping of a stock of transformers for these different line connecting apparatuses for each of these possible voltage values, their primary winding is subdivided in the manner that 110 volt as well as 220 v. may be connected to the transformer whereby the delivered secondary voltage remains the same. Furthermore such line tap devices are equipped in the manner that the current required for the feeding of the cathodes of the rectifier tube or of the amplifier tubes is not directly taken from the line tapping transformer, but is first conveyed from the secondary side of this transformer to a second heating transformer wherein is accomplished the reduction to the required heating voltage, or heating voltages.

If it is desired to use in such line tapping devices with double transformation a hydrogen-iron resistance in the usual manner, that is, in the primary circuit, for maintaining the constancy of the current the necessity arises to keep in stock hydrogen-iron resistances for various line voltages. It is an object of this invention to eliminate this disadvantage by connecting the hydrogen-iron resistance in the connecting line between the two transformer stages. This connecting line always carries a uniform voltage regardless of whether the tapped line has 110 or 220 volts. It is thus seen that with the arrangement described herein only a single type of hydrogen-iron resistances is made use of. This arrangement has the further advantage that with the tapping of different heating voltages from the heating transformer proper, only one hydrogen-iron resist-

ance is required as compared to a plurality corresponding to the cathodes to be heated.

The invention is represented in the drawing the single figure of which shows diagrammatically a preferred embodiment of the invention.

The line tapping transformer T is provided with a symmetrically sub-divided primary coil of four parts a_1, a_2, a_3 and a_4 . The secondary b leads through a hydrogen-iron resistance c to the primary d of the heating transformer Th. The heating transformer is provided with two secondary coils of which the one d_1 is used for feeding the cathodes of the rectifier tubes e, e_1 . The other secondary d_2 may be employed for feeding the cathodes of amplifier tubes which are to be operated with the line tapping apparatus. The plates of the rectifier tube are connected to a secondary coil f of the line tapping transformer T, from whose mid-point the one line g leads to the steadyng circuit, consisting of choke coil-resistances and condensers, and from there to the utilization apparatus. The second line g_1 is branched off from the connecting line between the two cathodes of the mentioned rectifier tube.

While the invention is shown as applied to a full wave rectifying arrangement it is obvious that any type of rectification system may be used such as a half wave rectifier or a single tube full wave rectifier and that any such adaptations are clearly within the scope of the appended claims.

Claims:

1. In a device of the kind described, rectifying devices having anodes and hot cathodes, an input transformer having means for allowing said system to be connected to any one of a plurality of different line voltages without changing the voltage across the secondary winding thereof, said secondary winding being adapted to maintain said anodes at proper potentials with respect to said cathodes, an auxiliary secondary winding and a voltage regulating device, a second transformer having a secondary winding thereof adapted to energize the cathodes of the rectifying devices, the primary circuit thereof, said auxiliary secondary wind-

ing and said voltage regulating device being connected in series so as to form an electrical circuit and an auxiliary secondary winding for said second named transformer for supplying energy to a load.

5 2. In a rectifying system utilizing at least one rectifying device comprising an anode and a hot cathode, an input transformer having a plurality of primary windings and a secondary winding, said secondary winding being connected across the anode and cathode of said rectifying device, an auxiliary secondary winding, a voltage regulating device, said primary winding being adapted to allow said system to be connected to anyone of a plurality of different line voltages without changing the voltage across said secondary, a second transformer, a secondary winding thereof being connected across the cathode of the rectifying device, the primary circuit thereof forming a series circuit with the said auxiliary secondary winding and said voltage regulator, and an auxiliary secondary winding for said second named transformer.

30 3. In a rectifying system, comprising in combination, rectifying devices having anodes and hot cathodes, an input transformer having means for allowing said system to be connected to any one of a plurality of different line voltages without changing the voltage across the secondary winding thereof, said secondary winding being connected across the anodes and cathodes of said rectifying devices, an auxiliary secondary winding for said transformer, a second transformer having a secondary winding thereof connected across the cathodes of the rectifying devices for heating same, a voltage regulating device, the primary circuit of said second transformer, said auxiliary secondary winding and said voltage regulating device being connected in series so as to form an electrical circuit and an auxiliary secondary winding for said second named transformer for supplying energy to a load.

40 4. In a rectifying system utilizing at least one rectifying device having an anode and a hot cathode, an input transformer having a primary winding and a secondary winding, said secondary winding being connected in series with a load and across the anode and cathode of said rectifying device, an auxiliary secondary winding, a voltage regulating device, a second transformer, a secondary winding thereof being connected across the cathode of the rectifying device, the primary circuit thereof forming a series electrical circuit with said auxiliary secondary winding and said voltage regulating device, and an auxiliary secondary winding for said second named transformer for supplying energy to a load circuit.

55 5. In a device of the kind described, rec-

70 tifying means having anodes and hot cathodes, an input transformer having means for allowing said system to be connected to any one of a plurality of different line voltages without changing the voltage across the secondary winding thereof, an auxiliary secondary winding for said transformer, a second transformer having a secondary winding thereof connected across the cathodes of the rectifying devices for supplying energy thereto, a voltage regulator, the primary circuit of said second transformer, said auxiliary secondary winding and said voltage regulator being connected in series so as to form an electrical circuit and an auxiliary secondary winding for said second named transformer for supplying energy to a load.

75 In testimony whereof I affix my signature.
